CLAIM

The ornamental design for a chair and table set, as shown and described.

DESCRIPTION

FIG. 1 is a perspective view of a first embodiment of a chair and table set showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a perspective view of a second embodiment of a chair and table set showing my new design;

FIG. 8 is a front elevational view thereof;

FIG. 9 is a rear elevational view thereof;

FIG. 10 is a left side elevational view thereof;

FIG. 11 is a right side elevational view thereof;

FIG. 12 is a top plan view thereof;

FIG. 13 is a perspective view of FIG. 1 without the table, shown in an alternate position; and,

FIG. 14 is a perspective view of FIG. 7 without the table, shown in an alternate position.

The broken lines in the drawings depict portions of the chair and table set that form no part of the claimed design.

1 Claim, 14 Drawing Sheets
